UNITED STATES PATENT OFFICE

JOHN CASTELLI, OF CARNEGIE, PENNSYLVANIA

TORCHÈRE

Application filed January 28, 1930. Serial No. 423,999.

This invention relates to torches or torchères, and the primary object of this invention is to provide a torch which will present a neat, attractive appearance and which may be set up in a cemetery upon or beside a grave, the object of the invention being further to provide a torch wherein the illuminating element of the torch may be in the nature of slow burning oils or a candle arranged within a suitable globe or glass casing mounted on a suitable supporting structure.

A still further object of the invention is to provide in a torch of the above mentioned character novel means for supporting the cup receiving the oil or candle within the globe or glass container.

Other objects and advantages of the invention will become apparent during a study of the following description, taken in connection with the accompanying drawings wherein:

Figure 1 is an elevational view of a torchère embodying the features of the present invention,

Figure 2 is a longitudinal vertical sectional view therethrough,

Figure 3 is a fragmentary top elevational view showing a modified form of globe or glass casing,

Figure 4 is a fragmentary longitudinal sectional view through the upper end of the supporting post illustrating a modified form of retaining means for the candle or oil cup;

Figure 5 is an elevational view of the preferred form of holder,

Figure 6 is a side elevational view thereof,

Figure 7 is a fragmentary detail sectional view taken substantially on the line 7—7 of Figure 1,

Figure 8 is a vertical transverse sectional view taken through the cap,

Figure 9 is a transverse sectional view taken substantially on line 9—9 of Figure 3.

With reference more in detail to the drawings, and more in particular to Figures 1, 2 and Figures 5 to 8 inclusive it will be seen that my improved torchère has a leg supporting base 5 from which rises a standard 6. The lower end or base of the standard 6 is relatively solid as at 7 and the upper end of

the standard 6 includes a relatively elongated solid portion 8.

The standard 6 is preferably made of metal and the intermediate portion thereof is suitably shaped, while the solid portions 7 and 8 are suitably carved and otherwise formed and shaped for enhancing the appearance of the standard.

Thus as shown in the drawings the base 5 and standard 6 will present an attractive and decorative appearance. An elongated rod 9 extends through the standard 6 and base 5. Socket member 10 is threaded on the lower end of the rod 9 beneath the base 5 and the socket member 10 has threaded therein the upper end of an anchor bar 11. The bar 11 is pointed at its lower end and the bar 11 may be driven into the ground for anchoring the torch in place.

A nut 12 is suitably secured on the upper end of the rod 9. A substantially cup-shaped member 13 has an apertured bottom wall the aperture 15 of which is internally threaded for threaded engagement with the threaded reduced portion 14 of the nut 12. (See Figure 7.) At its open upper end the cup shaped member 13 merges into an outstanding annular flange upon which is formed an upwardly extending annular rim 16.

The cup shaped member 13 may be decorated exteriorly as suggested in Figure 1 or may be of somewhat polygonal cross section as suggested in Figure 3. Any manner of shaping or otherwise decorating the cup shaped member 13 as to enhance and beautify its appearance may be utilized. An open ended glass cylinder 17 has the lower end thereof disposed within the confine of the rim 16, the lower edge of the cylinder resting upon the horizontally disposed annular flange portion of the cup 13, which annular flange portion is designated by the reference character 13'.

For securing the glass cylinder upon the cup member 13 set screws 18 are threaded through suitable apertures provided therefor in the rim 16, and the inner end of the set screws 18 bight or bear against the wall of the cylinder. If desired, the cylinder 17 may be of any decorative nature. A cap 19 pref-

erably formed of metal fits over the upper end of the cylinder 17 for closing said upper end.

The cap 19 has a disk like body portion merging into a down turned annular flange or rim 20. Suitable spring members 21 are secured to the rim 20 at spaced circumferential points thereon for frictional engagement with the upper edge of the cylinder 17 for retaining the cap on the upper end of the cylinder.

The disk like body portion of the cap merges into a centrally located raised crown portion 22. An annular series of air holes 23 are formed in the upper end portion of the crown 22.

A sling or cradle 24 is preferably made of a single strand of wire bent to provide a substantially rectangular frame including side members 25 and upper and lower end or connecting members 26 and 27 respectively. An annular rimmed pan 28 is mounted in the lower end of the sling or cradle 24 and is bolted or otherwise secured to the end member 27 of the cradle as indicated at 29.

Adapted for disposition within the pan 28 is a glass cup or container 30. The cup 30 is adapted to receive a suitable candle fitting conformably therein or in lieu of a candle slow burning oil.

A substantially dome shaped plate 31 has mounted thereon a cross 32 and other decorations such as angels or the like 33. A threaded bolt 34 depends downwardly from the plate 31. The plate 31 is adapted to rest on the crown 22 of the cap 19, the bolt 34 extending through a suitable opening provided therefor in the top of the crown 22.

The top member 26 of the sling or cradle 24 is provided with a vertical bore 35 through which the bolt 34 extends and a nut 36 is threaded on the lower end of the bolt.

In practice then it will be seen that the upper end of the sling 24 fits snugly within the cap 19 and the sling extends downwardly into the cylinder 17 with the bottom member 27 of the sling resting in the cup shaped member 13.

In that embodiment of the invention shown in Figures 3 and 9 the globe instead of being cylindrical as in the aforementioned embodiment of the invention, is in this instance, in the form of a polygonal casing.

The polygonal shaped globe or casing is designated generally by the reference character 37. Said casing 37 comprises a suitable metallic frame structure designated generally by the reference character 38 within which frame structure are mounted a plurality of glass panels 39. The globe or casing 37 tapers toward its lower end and is open at its top and bottom.

The lower end of the casing fits within the confines of the rim 16 of the cup shaped member 13 and supported on top of the casing is a

suitable cap 40. The cap 40 may be of any suitable structure preferably similar to the cap 19, in that it is provided with an apertured dome 41 upon which is supported and secured in any suitable manner the plate 31 carrying the cross 32 and the mannikin 33.

Preferably, when using the polygonal shaped casing 37 which casing is also opened at its front, having a door 42 hinged in the opened front of the casing, the sling 24 is dispensed with. In lieu of the sling, and as shown to advantage in Figure 4, the pan 28 has its bottom resting on a collar 29 on the upper threaded end of the rod 9. In this instance, the upper threaded end of the rod 9 is extended up into the cup shaped member 13 and the pan 28 is secured to the upper threaded end of the rod 9 through the medium of a suitable nut 43 threaded on said upper end of the rod.

Of course mounted in the pan 28 will be the glass cup or container 30 in the usual manner.

From the foregoing then it will be seen that I have devised a thoroughly practical torchère especially adaptable for use in cemeteries whereby a light may be kept burning for a considerable length of time over a grave without continual attendance. It will be also appreciated, that a torchère embodying the features of the present invention, is simple in construction, consists of but comparatively few parts, can be readily assembled or disassembled, and when assembled will present a very attractive and pleasing appearance fully in keeping with the purpose for which it is designed.

Even though I have herein shown and described the preferred embodiments of my invention, it is to be understood that the invention is susceptible to changes fully comprehended by the spirit of the invention as herein described, and the scope of the appended claim.

Having thus described my invention, what I claim as new is:

In a torch of the character described, a base, a hollow standard rising from the base, a globe on the upper end of said standard having its upper end open, a cap fitted over the open end of the globe and being provided with spring fingers for releasably securing the cap in position, said cap having a dome rising from its center, a canopy resting upon the dome, a sling fitted in said globe having an open pan with an upstanding rim, a container in said pan, and means connecting the said sling and said cap to the canopy for removal from the globe as a unit.

In testimony whereof I affix my signature.

JOHN CASTELLI.
